CLOTHES WRINGER GUARD

Nicholas G. Pfeil, Oshkosh, Wis.

Application November 30, 1934, Serial No. 755,400

1 Claim. (Cl. 68—32)

This invention appertains to clothes wringers, and more particularly to means for preventing the fingers of the laundress from being caught between the wringer rolls incident to the feeding of clothes therebetween.

In the operation of clothes wringers, often painful injuries are caused from persons having their fingers caught between the wringer rolls. This is particularly true where the wringer is power-driven, such as in clothes washing machines. In some cases the clothes have to be pushed between the rolls, which results in the fingers being caught.

My invention has for one of its primary objects the provision of a novel attachment, which can be readily secured to conventional clothes wringers either of the hand or power-driven type, and which will form an efficient means for guiding the clothes between the wringer rolls, and effectively prevent the fingers from coming into close proximity to the rolls, whereby danger of the fingers being caught is prevented.

Another important object of my invention is to provide a combination safety guard and clothes feeding attachment for wringers, the device embodying an inclined feed plate attached to the frame of the wringer, and terminating in front of and substantially between the wringer rolls, and a guard plate overlying the feed plate, the guard plate terminating a sufficient distance away from the wringer rolls to prevent the hands of the operator from reaching the wringer rolls incident to the feeding of the clothes to the rollers between the guard and feed plates.

A further object of my invention is to provide an improved safety attachment for clothes wringers of the above character, which will be durable and efficient in use, one that will be simple and easy to manufacture, and one which can be placed upon the market at a reasonable cost.

With these and other objects in view, the invention consists in the novel construction, arrangement, and formation of parts, as will be herein-after more specifically described, claimed, and illustrated in the accompanying drawing, in which drawing:—

Figure 1 is a vertical section through a wringer and my improved attachment, the view being taken substantially on the line 1—1 of Figure 2, looking in the direction of the arrows.

Figure 2 is a top plan view of my improved attachment applied to a clothes wringer.

Figure 3 is a front elevation of my improved attachment, showing the same connected with the

frame of a clothes wringer, only a fragment of the wringer being shown.

Referring to the drawing in detail, wherein similar reference characters designate corresponding parts, throughout the several views, the letter "A" generally indicates my improved attachment, and "W" a clothes wringer with which the same can be associated.

The clothes wringer "W" forms no part of my present invention, and has merely been illustrated to show the use of the novel attachment, and the wringer can be of any desired construction or make. As shown, the wringer includes side posts or uprights 5 and 6, connected together at their upper and lower ends by cross bars 7 and 8. The side posts or uprights 5 and 6 rotatably support the wringer rolls 9 and 10, and the top roll 9 can be urged by leaf spring 11, or the like, into intimate contact with the lower roll. These rolls 9 and 10 can either be power-driven or operated by hand, as can be well understood.

My novel attachment "A" includes side rails 15 and 16, to which can be secured in any desired manner a bottom feeding plate 17. This plate 17 is preferably formed from sheet metal, and can be slightly arched to facilitate the placing of the clothes thereon, and the feeding of the clothes between the wringer rolls. Secured to the upper faces of the side rails 15 and 16 is a top guard plate 18, which can also be formed from sheet metal. This guard plate 18 can have its outer edge rolled, as at 19, to form a stop for the hands of the operator, and to also facilitate the placing of the clothes between the guard and feed plates. By referring to Figure 1 it can be seen that the front edges of the plates 17 and 18 terminate in the same vertical plane, but that the outer end of the plate 18 terminates considerably short of the outer edge of the feed plate 17. This forms a convenient means of placing the clothes on the feed plate and for giving the clothes the initial push between the two plates.

The attachment "A" can be secured rigidly on the frame of the wringer "W" in any desired way, and for the purpose of illustration I have shown side angle brackets 20 and a bottom angle bracket 21 for this purpose. In all events it is essential that the forward end of the feed plate terminate adjacent to the meeting point of the wringer rolls 9 and 10 so that as the clothes are fed thereover, the rolls will grip the clothes so as to feed the clothes between the same.

The side rails 15 and 16 preferably diverge toward their outer ends so as to provide a wide flaring mouth, and if desired the plates 18 and 17

can also diverge away from one another toward their outer ends.

It is essential that the width of the wringer plate 18 be greater than the length of the operator's hands so that as the operator pushes the clothes into the attachment, and between the plates 17 and 18, all danger of the fingers being caught by the rolls will be eliminated.

From the foregoing description it can be seen 10 that I have provided an exceptionally simple and efficient means for feeding clothes between the rolls of a clothes wringer without danger of the fingers of the operator being caught between the rolls.

15 Changes in details may be made without departing from the spirit or the scope of this invention, but what I claim as new is:—

As a new article of manufacture, a guard and

clothes-feeding attachment for clothes wringers comprising a pair of side bars having flat upper and lower faces, said side bars diverging toward their outer ends and gradually increasing in thickness toward said outer ends, a feed plate secured to the lower faces of the side bars, a guard plate secured to the top faces of the side bars, the inner ends of the plates terminating substantially in the same vertical plane, the outer end of the guard plate being rolled back 5 defining a stop flange, and said feed plate having a portion extending a material distance forwardly of said rolled end of the guard plate constituting an initial clothes-receiving member, and brackets carried by the guard for rigid connection with a clothes wringer. 10 15
